UNITED STATES PATENT OFFICE

ALFRED LAGASSE, OF FALL RIVER, MASSACHUSETTS

LOOM TEMPLE ROLL

Application filed August 30, 1929. Serial No. 389,574.

The present invention relates to temple-rolls and contemplates rubber covered rolls of special construction which are effectively engaged and hold the fabric taut without puncturing or otherwise injuring the fabric, and more especially with finer grades of cotton and silk.

The nature and advantages of the invention will be better understood when the following detail description is read in connection with the accompanying drawing, the invention residing in the construction, combination and arrangement of parts are claimed.

In the drawing forming part of this application like numerals of reference indicate similar parts in the several views and wherein:

Figure 1 is a view in elevation of the invention.

Figure 2 is a sectional view on line 2—2 of Figure 1.

Figure 3 is a view partly in section of one of the rolls.

Referring to the drawing in detail, it will be noted that the rolls are used in pairs, and are journaled in a suitable holder 10 which may vary in construction without departing from the inventive idea. In accordance with the present invention each roll includes a hollow wooden core 11 which is covered by rubber 12, the latter being formed with a spiral groove 13 throughout its length, thereby defining spaced annular rest portions 14. The rolls are arranged side by side, and the right hand roll indicated at A in Figure 1 is provided with a right hand spiral groove, while the roll indicated at B in Figure 1 is provided with a left hand spiral groove. The raised annular portions 14 on each roll are also cut to provide longitudinally disposed teeth 15, although these raised portions may be substantially roughened or serrated in any suitable manner to effectively engage the fabric and hold the latter taut as it is woven on the loom, without any possibility of doing injury to the fabric.

While it is believed that from the foregoing description, the nature and advantages of the invention will be readily apparent, I

desire to have it understood, that I do not limit myself to what is herein shown and described and that such changes may be resorted to when desired as fall within the scope of what is claimed.

What is claimed is:

A pair of temple rolls, a holder in which said rolls are journaled side by side, each roll including a hollow core and a covering of rubber therefor, the covering of one roll having a right hand spiral groove formed therein, the other covering having a left hand spiral groove formed therein, said grooves defining each covering with uniformly spaced annular disposed portions, and teeth formed on the peripheries of said annular portions for the purpose specified.

In testimony whereof I affix my signature
ALFRED LAGASSE.
